UNITED STATES PATENT OFFICE

2,634,443

SPRING BRUSH CONTROL FOR CARPET SWEEPERS

Fred W. Pullen, Grand Rapids, Mich., assignor
to Bissell Carpet Sweeper Company, Grand
Rapids, Mich., a corporation of Michigan

Application March 30, 1946, Serial No. 658,498

5 Claims. (Cl. 15—41)

1

This invention relates to improvements in spring brush control for carpet sweepers.

The main objects of this invention are:

First, to provide a carpet sweeper in which the brush is automatically adjusted to proper sweeping position or relation to the varying lengths or depths of nap of carpets or rugs on which the sweeper is used and without regard to the degree to which the wheels of the sweeper may be pressed into the nap or the downward thrust applied to the sweeper.

Second, to provide a carpet sweeper in which the rotary brush is yieldingly urged to the surface to be cleaned and at the same time one in which the spring biasing stress on the brush remains approximately constant throughout the range of vertical movement of the brush relative to the floor wheels of the sweeper.

Third, to provide a carpet sweeper which is very easily operated and one which does not depend on the skill of the operator for effective sweeping.

Fourth, to provide a carpet sweeper embodying these advantages which is economical in its parts and very durable in use and one which does not unduly wear or injure the carpet or rug on which it is used.

Objects relating to details and economies of the invention will appear from the description to follow. The invention is defined and pointed out in the claims.

Preferred embodiments of the invention are illustrated in the accompanying drawing, in which:

Fig. 1 is an end elevation of a carpet sweeper embodying my invention, parts being broken away to better disclose structural details.

Fig. 2 is an enlarged fragmentary view mainly in horizontal section on a line corresponding to line 2—2 of Fig. 1.

Fig. 3 is an enlarged fragmentary end elevational view of a modified form or embodiment of my invention.

Fig. 4 is a fragmentary view showing another modification or embodiment of my invention.

Fig. 5 is an enlarged fragmentary view partially in vertical section on line 5—5 of Fig. 3.

Fig. 6 is a perspective view of the journal member or slide shown in Figs. 3 and 5 prior to the assembly of the spring therewith.

My present invention is an adaptation of the invention of my Letters Patent No. 2,418,725, issued April 8, 1947. I have shown only one end of the sweeper structure but it will be understood that the parts are duplicated on the other

2

end of the structure. Further, certain parts are conventionally shown and only such parts are detailed as is deemed necessary to give a complete understanding of a practical commercial embodiment of my invention.

Referring to the drawing, the casing is designated generally by the numeral 1 and comprises side members 2 and end members 3 arranged in an inset relation relative to the ends of the side members.

The end bar 4 in the structure illustrated extends across the sweeper from the ends of the side members, being secured thereto. This end bar or member 4 is, in the embodiment illustrated, relatively narrow but in some types of sweepers it is substantially of the contour and width of the end member of the casing. Such an end member is not illustrated as it is known in the art.

The floor wheels 5 are provided with floating axles 6 which are disposed longitudinally through the casing and end members 3, this also being disclosed in prior patents of the applicant.

The bowed spring 7 is mounted on the angled bracket 8 secured to the end member of the casing so that the bracket depends at the outer side of the pulley 9 of the brush 10. The ends of the spring 7 are secured to the arms 11 of the wheel bearing members 12, this mounting and biasing of the floor wheels being, as stated, shown in prior patents issued to the applicant and therefore not detailed herein. The pulley 9 is operatively associated with the floor wheels to be driven thereby.

The brush is mounted for vertical floating movement, the journal 13 of the brush being provided with a slide 14 having laterally offset flange-like slideway engaging members or portions 15. The bracket 8 is conformed to provide a vertical slideway 16 receiving the journal member 14 for vertical sliding movement.

In the structure illustrated, the end member 4 extends across the bracket providing a support therefor and preventing outward movement of the slide or journal member in the slideway although, in the structures illustrated, the brush tensioning spring 17 extends through the journal member so that it also prevents outward movement of the journal member as is clearly shown in Fig. 2. However, the bar 4 serves as a guard for the bracket and slide and in the embodiment illustrated constitutes an outer bearing member for the slideway engaging parts 15 of the journal member.

The bracket 8 and the slideway therein are

formed by stamping operations. The journal member slide is also a stamping.

The brush journal member is yieldingly urged downward by means of the spring 17 which in the embodiment illustrated is a reversely bowed spring. The ends of the spring are fixedly secured to the bar 4 by striking in loops 18 in the bar, the ends of the spring being inserted through these loops and the parts crimped as indicated at 19 to positively fixedly secure the ends of the spring against sliding movement in the general longitudinal direction of the spring. The bowed or bent reaches of the spring are of such character that they spring laterally under endwise thrust resulting from the vertical movement of the journal member.

The spring 17 is disposed horizontally in approximately the horizontal plane of the journal member and is of such length that the bowed portions thereof flex throughout the full range of movement of the journal member without substantial variation in the biasing stress of the spring on the brush.

In the embodiment shown in Fig. 3, the brush biasing spring 20 is provided with coils 21 adjacent its ends which are down-turned at 22 and engaged through loops 23 struck in from the end bar 4. In this embodiment the coils increase the length of the spring and also serve to receive and absorb the end thrust that may result from the vertical movement of the journal member. In this structure, the journal or slide member has slots 24 formed therein receiving the spring, the bottom edge 25 of the web of the slide being folded forwardly around the spring as is shown in detail in Figs. 5 and 6. It will be noted that the spring 20 is bowed substantially the same as the spring 17 but has the additional feature of the coils.

In the embodiment of my invention shown in Fig. 4, the brush tensioning spring 25 is substantially straight and is provided with coils 26 which increase the length thereof and serve the further purpose of absorbing such end thrust as results from the vertical movement of the slide 27. In this case, the slide is secured to the spring by means of a tongue 28 folded over the spring instead of under it, this in effect being a reversal of the position of the slide to accommodate the unbowed spring. In this embodiment of Fig. 4, the ends of the spring are secured in brackets 29 mounted on the casing end member 3. The brackets have loops 30 struck out therefrom to receive the down-turned ends 31 of the spring.

By this arrangement of parts, I provide a structure in which proper sweeping action is maintained whether the sweeper is used on a floor, carpet or rug or on rugs or carpets of varying depth of nap as the biasing stress of the spring on the brush does not vary greatly but remains substantially constant throughout the full range of movement of the brush relative to the floor wheels and other parts of the structure. This is of very great importance as it prevents undue sweeping or brush action on delicate rugs or carpets having long or deep nap and this without regard to the skill of the operator.

In carpet sweepers of commercial types other than the one shown in my said application for Letters Patent it has been the practice so far as applicant is aware to provide structures in which the pressure on the handle is the controlling feature as to brush action. The applicant has departed from this principle of operation and has

provided a structure in which the sweeping action not only is not dependent on the pressure thrust which the user may exert but remains substantially constant despite such thrust that may be imparted by the user, it being the applicant's purpose and accomplishment of this invention to secure an efficient sweeping action without regard to the manipulation by the use other than the mere matter of translating the sweeper back and forth on the surface to be swept and to secure such efficient sweeping action with a minimum of wear on the carpets or rugs or injury to the nap thereof.

I have illustrated and described my invention in practical embodiments thereof. I have not attempted to illustrate or describe other adaptations or modifications thereof as it is believed that this disclosure will enable those skilled in the art to embody or adapt my invention as may be desired.

Having thus described my invention, what I claim as new and desire to secure by Letters Patent, is:

1. In a carpet sweeper, the combination with a casing comprising side members and an end member, said side members being disposed on opposite sides of said casing, floor wheels disposed on the outer side of the end member, a brush provided with a pulley cooperatively associated with the floor wheels, a bracket mounted on the casing end member to depend at the outer side of the pulley, said bracket being provided with a vertical slideway, an end bar disposed on the outer side of said bracket, a brush journal member mounted on said slideway for vertical movement, and an elongated horizontally disposed reversely bowed spring engaged substantially centrally thereof with said journal member and secured at its outer ends to said end bar in spaced relation from the opposite sides of said journal member, the spring being disposed generally horizontally in approximately the horizontal plane of the journal member, said reversely bowed spring being bowed vertically a substantial distance from the general horizontal plane of the spring in portions thereof on opposite sides of said journal member and having its outer ends positively fixedly secured to said end bar against sliding movement in the general longitudinal direction of the spring, said bowed portions of the spring permitting substantial vertical movement of the journal member connected to the central portion of the spring without sliding movement of the fixed ends of the spring in the general longitudinal direction of the spring, said connection of the ends of the spring to the end bar being adjacent said side members on the opposite sides of the casing, said spring being of such length that the bowed portions thereof flex throughout the full range of movement of the journal member so that the biasing stress of the spring on the brush is approximately constant throughout the range of vertical movement of the brush from initial position.

2. In a carpet sweeper, the combination with a casing and floor wheels, of a brush provided with a pulley operatively associated with said floor wheels, a support member carried by the casing and disposed at the outer side of the pulley, said support member being provided with a slideway, a journal member for said brush mounted on said slideway for vertical movement, and an elongated generally horizontally disposed spring connected substantially centrally thereof to said

brush journal member, and means on said casing adjacent the opposite sides of the casing to which the opposite ends of said spring are connected in spaced relation from the opposite sides of said journal member, said spring being disposed horizontally in substantially the plane of the journal member, said means for connecting the ends of the spring to the casing positively fixedly securing said ends to the casing against sliding movement thereof relative to the casing in the general longitudinal direction of the spring, said spring having portions thereof bowed vertically a substantial distance from the general horizontal plane of the spring on opposite sides of said journal member, said bowed portions of the spring facilitating vertical movement of the central portion of the spring connected to said journal member without longitudinal sliding movement of the fixed ends of the spring, said spring of such length and its bowed portions being such that the biasing stress thereof is approximately constant throughout the range of vertical movement of the brush.

3. In a carpet sweeper, the combination with a casing and floor wheels, of a brush provided with a pulley operatively associated with said floor wheels, a support member carried by the casing and disposed at the outer side of the pulley, said support member being provided with a slideway, a journal member for said brush mounted on said slideway for vertical movement, an elongated substantially horizontally disposed rod spring connected substantially centrally thereof to said brush journal member, and means on said casing adjacent opposite sides thereof with which the ends of said spring are secured in spaced relation from the opposite sides of said journal member, said spring being disposed horizontally in substantially the plane of the journal member and being provided with coils between said journal member and the ends of said spring and being of such length that the biasing stress thereof is approximately constant throughout the range of vertical movement of the brush, said means positively fixedly securing the ends of the spring against sliding movement thereof relative to the casing in the general longitudinal direction of the spring, one of said coils being disposed along the spring between the journal member and one of the secured ends of the spring, another of said coils being disposed along the spring between the journal member and the other secured end of the spring, said coils extending vertically a substantial distance from the general horizontal plane of the spring. 50 45 35

4. In a carpet sweeper, the combination with a casing and floor wheels, of a brush provided with a pulley operatively associated with said floor wheels, a support member mounted on said casing and having a vertical slot providing a slideway, a journal member for said brush mounted on said slideway for vertical movement at the outer side of the pulley, said journal member including a U-shaped slide projecting through said slot, the arms of the U-shaped slide being provided with flanges retainingly engaging the outer side of the support member, an elongated sub-

stantially horizontally disposed spring connected substantially centrally thereof to said brush journal member, and means on said casing to which the opposite ends of the spring are connected in spaced relation from the opposite sides of said journal member, said spring being disposed horizontally in substantially the plane of the journal member and being provided with portions bowed vertically a substantial distance from the general horizontal plane of the spring, said bowed portions being disposed on the opposite sides of the journal member between said journal member and the points of connection to said means at the opposite ends of the spring, said means for connecting the ends of the spring to the casing positively fixedly connecting said ends to the casing against sliding movement generally longitudinally of the spring, said means connecting the ends of the spring to the casing adjacent the opposite sides thereof, the spring being of such length that the biasing stress thereof is approximately constant throughout the range of vertical movement of the brush.

5. In a carpet sweeper, the combination with a
25 casing and floor wheels, of a brush provided with
a pulley operatively associated with said floor
wheels, a support member carried by the casing
and having a vertical slot providing a slideway
disposed at the outer side of the pulley, a jour-
30 nal member for said brush mounted on said
slideway for vertical movement, said journal
member including a U-shaped slide projecting
through said slot, the arms of the U-shaped
35 slide having flanges retainingly engaging the out-
er side of the support member, said arms having
open ended vertical slots, an elongated substan-
tially horizontally disposed spring having its cen-
tral portion disposed in said slots, and means on
40 said casing to which the opposite ends of said
spring are connected, said slide having a web
portion intermediate the arms thereof bent over
the central portion of the spring for retaining
the spring in the slots, said connecting means
45 positively fixedly securing the opposite ends of
the spring to the casing against sliding move-
ment in the general longitudinal direction of the
spring, said connecting means connecting the
ends of the spring to the casing adjacent the
50 opposite sides thereof, said spring having por-
tions thereof bowed vertically a substantial dis-
tance from the general horizontal plane of the
spring on opposite sides of said journal member.

FRED W. PULLEN.
